Design No. 3,444, dated April 6, 1869.

DESIGN FOR A TRADE-MARK

The Schedule referred to in these Letters Patent and making part of the same.

To all whom it may concern:

Be it known that I, ALFRED RAY, of the city of Chicago, county of Cook, and State of Illinois, have originated and designed a new Design for a Trade-Mark, of which the following is a full, clear, and exact description, reference being had to the accompanying specimen or drawing, making part of this specification.

This design for a trade-mark consists of a card or label having in the centre the figure of a tiger, and above it, in letters, the words "Tiger-make," and on one side a medallion, enclosing, in letter-press, the words, "Unequalled in shade, weight, and quality," and on the other a similar medallion, enclosing the

words, "Silk-finished alpaca, Paris Exhibition," and also the abbreviations "No." and "Yds.," and below the figure of the tiger the abbreviations and words, "Ent'd at" "Trade-Mark" "Sta's Hall."

Claim.

What I claim as my invention, and desire to secure by Letters Patent, is—

The design for a trade-mark, herein set forth and shown.

ALFRED RAY.
